UNITED STATES PATENT OFFICE.

WILLIAM PEARCE, OF BIRMINGHAM, ENGLAND.

BOTTLE STOPPER AND MOUNT.

SPECIFICATION forming part of Letters Patent No. 536,700, dated April 2, 1895.

Application filed December 10, 1894. Serial No. 531,314. (No model.)

To all whom it may concern:

Be it known that I, WILLIAM PEARCE, a subject of the Queen of Great Britain, and a resident of 52 Hylton Street, in the city of 5 Birmingham, England, have invented new and useful Improvements in Bottle Stoppers and Mounts, of which the following is a specification.

My invention relates to improvements in 10 connection with bottle mounts and bottle stoppers, and more particularly referring to such bottles that are used for smelling salts or other liquids or substances when it is desirable that the said stopper shall be secured 15 in its place by an external mount or other device.

The object of this my invention is to combine with the usual stopper, or such other suitable stopper, a part rotating locking device of the construction and arrangement as hereinafter described. I attain these objects by the mechanism illustrated in the accompanying drawings, in which—

Figure 1, shows an external view of my invention. Fig. 2, is a plan view of my invention with the stopper knob removed. Fig. 3, is a sectional view of the invention on line A—B. Figs. 4, 5, 6 and 7, are detailed views of some of the mechanical parts employed in 30 this my invention. Fig. 8, is a detached view of the stopper.

Similar numbers refer to similar parts throughout the several views.

10, is the bottle.

35 11 is the stopper fitting the throat 12 of the bottle, and having the terminal knob or handle 13, and the neck 14. Upon the exterior of the neck of the bottle is fixed the mount 15, having the upper plate 16, secured thereto. 40 Upon this plate are carried a number of plates 17, which are movably jointed at 18. At the other ends of these plates are projecting pegs or studs 19. I now provide the part rotative

plate 20, having the slot holes 21, corresponding in number to the number of pegs 19. This 45 plate 20, is now soldered within the outer collar 22, and then placed in position upon the plate 17, the pegs 19, taking into the slots 21. The lower edge 23, of the collar is now turned over the projecting edge 24, of the plate 16, 50 to prevent its removal see Fig. 3, but permitting a part rotative movement. By part rotating the said collar the plates are simultaneously drawn across the central opening, as seen in Figs. 2 and 7, or drawn back underneath the collar as seen in Fig. 6. It will now be seen that when the stopper 11, is in its place in the throat of the bottle (as seen in Fig. 3), by rotating the collar 22, the plates 17, are closed tightly around the neck 14 of 60 the said stopper, and thereby effectually prevents its removal. By turning the collar 22, in the opposite direction the plates 17, are all withdrawn leaving the central portion quite clear and free for the removal of the stopper. 65

It will be readily seen that the shape and detail of the various parts may be considerably modified without departing from the nature of my invention.

I am aware that a moving diaphragm of 70 this kind has already been used for mounts to cover or uncover certain openings and therefore I do not claim such mounts of themselves, but

What I claim, and wish to secure by Letters 75 Patent, is—

The combination with a bottle 10, stopper 11, of the plate 16, having the movable plates 17, and the part rotative collar 22, and plate 20, all substantially as described and shown, 80 and for the purposes specified.

WILLIAM PEARCE.
